(57) **CLAIM**

The ornamental design for the lighting fixture, as shown and described.

DESCRIPTION

FIG. 1 is a perspective view from below of a lighting fixture in accordance with my design;

FIG. 2 is a side elevation view of the lighting fixture in accordance with my design;

FIG. 3 is a top plan view of the lighting fixture in accordance with my design; and,

FIG. 4 is a bottom plan view of the lighting fixture in accordance with my design.

The broken lines showing environmental structure are for illustrative purposes and form no part of the claimed design.
